UNITED STATES PATENT OFFICE.

EDWARD C. CORDELL, OF SAN FRANCISCO, CALIFORNIA.

INTERNAL-COMBUSTION ENGINE.

Application filed December 23, 1919. Serial No. 347,048.

To all whom it may concern:

Be it known that I, EDWARD C. CORDELL, a citizen of the United States, whose residence is San Francisco, California, and whose post-office address is 886 Mills Building, San Francisco, California, have invented new and useful Improvements in Internal-Combustion Engines.

This invention relates to internal combustion engines.

The object of the invention is to provide such an internal combustion engine which will thoroughly scavenge or exhaust all burnt products of exploded gases from the combustion chamber after each explosion and thereby eliminating any possibility of lowering the efficiency of the incoming charge of explosive gas by admixture with exploded gases.

I accomplish the above by providing an auxiliary piston operating in the combustion chamber above the main piston within the same cylinder and so synchronized that the two pistons are brought together during the exhaust stroke of the main piston and thereby driving out all burnt gases.

With the above and other objects in view the invention consists in the novel features of construction, combination and arrangement of parts to be hereinafter more fully described, claimed and illustrated in the accompanying drawings, of which;

Figure 1 is an end elevation of an internal combustion engine illustrating the preferred embodiment of my invention.

Fig. 2 is a central vertical cross sectional view of Fig. 1.

Similar numerals refer to similar parts throughout the several views.

In the drawings I have illustrated the use of my invention as when applied to a four cycle internal combustion engine of the reciprocating type of which 10 is the cylinder and 11 the power piston which is provided with the usual rings 12 and connected to the crank shaft 13 through the connecting rod 14. The crank shaft 13 is suitably housed and mounted within the usual crank case which comprises the sections 15 and 16, and the upper section being provided with an outwardly extending circular portion 17, the purpose of which will later appear.

Above the main piston 11 and operable within the combustion chamber, I provide an auxiliary piston 18 provided with the

usual rings 19 and having a hollow stem 20 secured thereto. The stem extends through an opening provided in the head of the cylinder and carries a cap member 21 on its upper end. About the stem is positioned a coil spring 22 adapted to yieldingly hold the piston 18 in its raised position and against the cylinder head. Also the hollow stem 20 is provided with a suitable port 20' at each end in order to prevent the creation of a vacuum in the upper part of the engine cylinder on the downward stroke of the auxiliary piston.

Between the raised position of the auxiliary piston and the extreme upward stroke of the main piston, I suitably arrange in the walls of the cylinder a spark plug 23 and an exhaust and intake port 24.

In order to lower the auxiliary piston at the proper interval I provide a shaft 25 which is driven from the crank shaft 13 through the reduction gears 26, 27' and 28' at one-half the speed of the crank shaft, Fig. 1. On the shaft 25 there is mounted a cam 26 of substantially the shape as shown in Fig. 2 of the drawings. A rocker arm 27 is suitably pivoted or fulcrumed on the cylinder head and on each end carrying a roller 28 suitably journaled, one roller being adapted to engage the head 21 of the piston stem 20 and the other roller adapted to engage a head 29 provided on the upper end of a connecting rod 30. The connecting rod 30 is suitably mounted for vertical movement and on its lower end there is suitably journaled a roller 31, said roller being adapted to operatively engage the cam 26.

To permit the inlet of explosive gas and the expulsion of burnt gases into and from the combustion chamber of the cylinder 10 through the same port 24, there is provided a piston valve, the cylinder 32 of which is preferably, cast integrally with the cylinder 10 and its upper end being a continuation to provide a suitable exhaust 33. Near the lower end of the cylinder 32 and in the exterior side wall thereof there is provided an opening which communicates with the pipe connection 34 and said connection leading to the carburetor not shown, a hollow piston 35 provided with suitable rings is adapted to operate in the cylinder 32. In the opposite walls of this piston there is provided the respective openings 36 and 37 and rigidly secured to the lower end

of the piston is a connecting rod 38 which carries a roller 39 on its lower end, suitably journaled and adapted to operatively engage the cam 40, said cam being mounted 5 on the shaft 25. A coil spring 41 surrounds the connecting rod 38, its upper end engaging the piston 35 and its lower end engaging an outwardly disposed flange 42 provided on the cylinder 10, and to which the upper 10 portion of the crank case is bolted. The function of the spring is to normally hold the roller 39 in engagement with the cam 40.

In the operation of the engine as herein described, assuming that all the parts have 15 the position as shown in Fig. 2. In which instance the piston 11 is in its downward and intake stroke, the auxiliary piston 18 in its raised position, and the valve piston in position to permit the incoming gas 20 to flow from the connection 34 into the piston and from thence into the cylinder 10 through the ports 36 and 24. As before stated the shaft 25 rotates at one-half the speed of the crank shaft 13 and consequently upon the compression stroke of the piston 11 the shaft 25 will have rotated sufficiently to cause the cam 40 to lower the piston 35 enough to close the port 24. When 25 the compression stroke of the piston 11 is complete, combustion occurs. Upon the exhaust stroke of the piston the cam 40 exerts its greatest throw which is sufficient to draw the piston 35 below the exhaust and intake port 24 and thereby permit the expulsion 30 of exploded gases from the exhaust 33. Also during the exhaust stroke of the piston 11 the cam 26 is in position to lift the rod

30 and thereby through the rocker arm 27 lower the auxiliary piston 18 sufficiently to meet the piston 11 at the time of its extreme 40 exhaust stroke, and in this manner all exploded and burnt gases are expelled from the cylinder. When the piston 11 again starts on its intake stroke the piston valve 45 will be brought into the position shown in Fig. 2 and the auxiliary piston 18 will assume its raised position as shown by the same figure.

Having thus described my invention what I claim and desire to secure by Letters Patent is:

An internal combustion engine comprising 55 a cylinder of constant diameter provided with a head having an opening therein, a main piston working within the cylinder, an auxiliary piston within the cylinder and normally spaced from the main piston, a hollow valveless stem carried by the auxiliary piston projecting through the opening in the cylinder head and provided with ports therein, one of said ports opening direct to the atmosphere, while the other port opens to the space intermediate the auxiliary piston and the cylinder head for relieving the 60 vacuum, a rocker arm contacting with the stem, and means for operating the rocker arm and main piston to bring the pistons together during the exhaust stroke of the engine.

EDWARD C. CORDELL.
